UNITED STATES PATENT OFFICE

167,692

JUICE EXTRACTOR

James L. Hvale, Chicago, Ill., assignor to Ekco Products Company, Chicago, Ill., a corporation of Illinois

Application April 5, 1952, Serial No. 19,205

Term of patent 7 years

(Cl. D89—1)

To all whom it may concern:

Be it known that I, James L. Hvale, a citizen of the United States, residing at Chicago, county of Cook, State of Illinois, have invented a new, original, and ornamental Design for a Juice Extractor, of which the following is a specification, reference being had to the accompanying drawing, forming part thereof.

Fig. 1 is a side elevational view of a juice extractor, showing my new design.

Fig. 2 is a similar view showing the arms of the device in partly spread apart position.

Fig. 3 is a top view of the article as shown in Fig. 1.

Fig. 4 is a fragmentary sectional view taken along line 4—4 of Fig. 3.

Fig. 5 is a transverse section taken on line 5—5 of Fig. 3.

I claim:

The ornamental design for a juice extractor, as shown.

JAMES L. HVALE.
